FOREIGN PATENT DOCUMENTS

EM 005629839-0001 * 9/2018

Primary Examiner — Paula Allen Greene(74) *Attorney, Agent, or Firm* — Suiter Swantz pc llo(57) **CLAIM**

The ornamental design for a speaker, as shown and described.

DESCRIPTION

FIG. 1 is a perspective view showing our new design; FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof; and,

FIG. 7 is a bottom plan view thereof.

The broken line showing a handle, speaker covers, and user-interface buttons of FIGS. 1 through 7 form no part of the claimed design.

1 Claim, 7 Drawing Sheets(56)
